UNITED STATES PATENT OFFICE

123,104

DESIGN FOR A DRINK MIXER

Albert F. Saunders, Syracuse, N. Y., assignor to
T. N. Benedict Manufacturing Company, East
Syracuse, N. Y., a corporation of New York

Application August 21, 1940, Serial No. 94,539

Term of patent 7 years

To all whom it may concern:

Be it known that I, Albert F. Saunders, a citizen of the United States, residing at Syracuse, in the county of Onondaga and State of New York, have invented a new, original, and ornamental Design for a Drink Mixer, of which the following is a specification, reference being had to the accompanying drawings, forming part thereof.

Figures 1 and 2 are perspective views of the drink mixer, showing my design looking in opposite directions.

I claim:

The ornamental design for a drink mixer, substantially as shown.

ALBERT F. SAUNDERS.
